UNITED STATES PATENT OFFICE.

JAMES WHITELAW, OF ST. LOUIS, MISSOURI.

SEWING-MACHINE STITCH-FORMING MECHANISM.

1,190,833.

Specification of Letters Patent. Patented July 11, 1916.

Application filed November 24, 1913. Serial No. 802,733.

To all whom it may concern:

Be it known that I, JAMES WHITELAW, a citizen of the United States, residing at St. Louis, State of Missouri, have invented 5 certain new and useful Improvements in Sewing - Machine Stitch - Forming Mechanism, of which the following is a specification.

My invention relates to sewing machine 10 stitch forming mechanism, and in some of its features more particularly to a sewing machine for making blind chain stitches.

One of the objects of my invention is to provide a looper mechanism particularly 15 adapted for coöperation with a reciprocating needle to form chain stitches, which will be certain and uniform in its loop-handling functions under varying conditions in the work, due to different lengths 20 of feed movement between stitches, and other variations.

Another object of my invention is to provide such a looper mechanism of simple and efficient structure, not liable to get out of 25 order, easily manufactured and assembled, and readily repaired, if damaged.

A further object of my invention is to provide simple and effective coöordination 30 of the needle, looper, and take-up mechanisms, and to provide for the adequate association of these parts a simple and easily manufactured mechanism.

In the drawings, wherein I have illustrated an embodiment of my invention in 35 a form which I have found to be practically advantageous, Figure 1 is a front elevation of a chain-blind-stitch machine, with parts of its stitch forming mechanism exposed; Fig. 2 is an enlarged front elevation showing 40 the stitch forming mechanism in greater detail; Fig. 3 is a similar end view of the stitch forming mechanism and appurtenant parts; Fig. 4 is a detail in vertical cross section, showing the mounting of the needle bar and looper mechanism, the parts of the looper mechanism being shown in elevation; Fig. 5 is a sectional detail on line 5—5 of 45 Fig. 2, showing a cam mechanism; Fig. 6 is a detail of looper shaft driving gearing mechanism from the rear, or side of the machine away from the operator; Fig. 7 is an enlarged detail of the looper mechanism in one position with parts of the presser foot in section; and Fig. 8 and 50 9 are perspective views showing the needle 55

and looper relation in two positions, illustrating respectively the loop taking and loop presenting operations of the looper.

The frame 10 of the machine is suitably designed to provide the lower work carrying arm 11 and the upper arm 12 for carrying the stitch forming mechanism, the frame of the machine being preferably a hollow integral casting open at its front face and having the contained mechanism 60 protected by adequate detachable cover members 13 and 13', the cover 13 being retained as by latch screw and cam, 14, 14'.

The goods are handled in the machine through the coöperation of a relatively stationary presser foot 15 carried by the upper arm and feeding mechanism carried by the lower arm and supplemented by a plunger for elevating portions of the goods through the presser foot to the action of the needle. 70 Specifically, the machine shown has at its front end a vertical head post 16 to which the presser foot 15 is secured by screw 17, said presser foot extending transversely of the arm and having at its center an opening 18 flanked on its under side by solid surfaces for the feed to work against. 75

Fragments only of the work handling mechanism 19 are here shown, for, generally, feed mechanisms and plunger mechanisms sufficient for the purposes of the present invention are known in the art, and the particular work handling mechanism which I preferably employ is specifically described 80 in my co-pending application, Serial No. 802,732, filed November 24th, 1913. It suffices to say, therefore, that the feed dog 20 coöperating with the under side of the stationary presser foot receives an appropriate four-way motion and is supplemented by a 85 clamp member 21 raised to clamping position when the feed member is lowered and straddled by the limbs of the feed dog, said clamp member having associated therewith a plunger 22 registering with the presser 90 foot opening 18 and appropriately operated to raise the nodes *a* of the goods *A* through the presser foot opening for coöperation with the needle 30 as shown in Fig. 8. In the cyclic operation of these parts with respect to the needle reciprocation, it will be understood, when the needle is retracted the plunger rises through the presser foot opening to present a node of goods in the line of passage of the needle, the goods be- 95 100 105 110

ing clamped against the under side of the presser foot by the clamp member 21. The needle makes its penetrating stroke through such node of goods, entering and emerging from the same surface of the work; when the penetration is completed the plunger descends, and upon completion of the retraction of the needle the clamp 21 also retracts and the feed dog 20 performs its forward feeding motion, feeding the goods transversely across the lower arm from the front of the machine to the rear thereof; the feed disengaging the goods and the clamp 21 reengaging the same at about the time of commencement of the next penetrant stroke of the needle.

The needle 30, is of the curved variety, preferably having its point in line with its outer radius of curvature, and inclined to its path of reciprocation with its point nearer the plunger than its butt. Said needle is mounted to reciprocate transversely of the direction of feed, preferably at right angles thereto. To receive the needle the upper surface of the presser foot is preferably dished or concaved and a needle deflecting guide 31 is mounted thereon, to deflect the needle point toward alinement with the path of reciprocation, said guide having in its face a groove 31', the sides of the groove serving to prevent lateral displacement of the needle point.

The needle is carried by a needle bar 32 pivotally mounted on the frame post 16 vertically above the presser foot opening 18 and said arm has an upwardly extending finger 33 through which oscillating motion is imparted to the bar. For the reception of a concentric shaft member of the looper mechanism to be described the hub of the needle bar 32 is provided or connected with a sleeve or hollow shaft 34 taking through a bearing in the frame post 16 and itself affording a bearing for the concentric shaft. Motion is imparted to the needle bar by link 35 pivoted at 35' to the end of finger 33 and to a wrist pin 36 on a spiral gear wheel 37 carried by jack-shaft 38 which extends through the rear wall of the arm 12 to receive, beyond the rear wall of the machine, other mechanisms to be described. The gear 37 is driven in one-to-one relation by a spiral gear 39 which is carried by a main shaft 40, said main shaft extending horizontally from end to end of the upper arm 12 and projecting through bushed bearings in both end walls thereof. At its rear end said shaft bears a suitable hand wheel pulley 40' for power application thereto. Manifestly with the arrangement described the needle reciprocates once for every revolution of the main shaft.

From the main shaft 40 the mechanism for actuating the looper bar structure 41 is driven and timed. While, for some of

the purpose of my invention, a looper bar having a single point may be employed, and an operating mechanism as hereafter described is suitable for the operation of a single point looper, I find it to be distinctly 70 advantageous to employ a looper having two points or members, one of which is power moved in a six way path while the other, carried by the power-moved member, is operated, incidentally to its bodily movements, to coöperate with the power moved point in entering and spreading the loop. 75

In the specific construction shown, 42 indicates a looper point structure of which 43 is the power-receiving member preferably in the form of a flat metal piece having its edge presented toward the front of the machine and having at its lower end a foot 44 providing an elongated bottom and a slender toe 45 pointing toward the operator and beveled at its top. Pivoted to the member 43, as at 46, is a complemental looper member 47 in the form of a lever having its lower arm shaped to provide a point 48 vertically registering with the toe 45, said point terminating at a shoulder 49, and the member 47 so disposed that, as shown in Figs. 7 and 8, when the two looper members are closed together the point 48 rests upon and projects beyond the extremity of the toe 45 for the effect of a single point, and when the member 47 is rocked on its pivot 46 the point 48 separates from the toe 45 and shoulder 49 stands about in vertical alinement with the end of the foot 44. Member 47 has at its upper end a forwardly projecting finger 50 through which the opening movement is given to the member 47 and a spring 51 connecting said finger with the projection 52 on the member 43 tends normally to hold the looper parts in closed position. 95 100 105

The looper-point structure 42 as a whole is given a 6-way movement, "fore-and-aft", or lengthwise of the needle path to present 110 it to the needle at two points in the needle travel; "in and out", or transversely to the needle path, for engagement with or disengagement from the loop, and "up and down", to carry the loop above the presser 115 foot opening. For one component of its movement the looper bar 41 as a whole forms a lever of the first class and by movement of its upper end above its fulcrum, the in and out motions are communicated to the 120 looper point structure 42. Its fulcrum as such lever is shiftable fore-and-aft operating said looper bar as a lever of the third class, with its fulcrum at its upper end, for imparting such components of the 6-way 125 motion to the point structure and it is movable up and down to carry with it the looper bar.

Specifically the point structure as a whole is carried by a yoke 55, pivoted on screws 56, 130

carried by a fulcrum block 57 which is encompassed by the yoke. Above the yoke, the stem 58 forms a power receiving arm for in-and-out vibration and makes sliding engagement with the ball 59 socketed in a spherical recess in the extremity of a lever 60, such form of connection permitting universal displacement of the arm 58 with respect to its power lever 60 and making the end of lever 60 the fulcrum for the fore-and-aft vibration. The lever 60 is pivoted on a longitudinally extending shaft 61 projecting from a part on the frame post 16 whereon it is retained by a collar 62 and the power-receiving end of said lever 60 carries a roller 63 engaging in a cam groove 64 of a disk 65 mounted directly on the main shaft 40. Rotation of cam 65 acts through lever 60 to vibrate the upper end 20 of the looper lever in and out, said looper lever rocking on the pins 56 and moving only in a plane transverse to the needle path.

The fulcrum block 57 on which the looper lever fulcrums has pivotal connection, between spacer collars 67, with the wrist pin 67 which is disposed eccentrically to its supporting shaft 68 taking through the bore of needle arm shaft 34. A flange 69 on shaft 68 abuts against the needle arm and a gear pinion 70 is fastened on the rear extremity of the shaft, retaining it against displacement. Oscillation of shaft 68 to throw the wrist pin 67 past its vertical center shifts the fulcrum block 57 fore-and-aft with respect to the plane of in and out motion of the universal joint 59 and so contributes fore-and-aft movement to the looper point structure, carried as a whole by shaft 68, while the vertical displacement of the wrist pin in such oscillating traverse serves to elevate and depress the looper point structure, its stem 58 sliding accommodately in the ball 59. Motion is imparted to the pinion 70 by a geared segment 71 mounted on shaft 72 carried by the frame and having pivoted link connections 73 with a wheel 74 fast on the shaft 38, such connection serving to reverse the direction of motion of looper carrying shaft 68 with respect to needle bar shaft 38, and to give to the rock shaft 68 the desired angular range of movement between its limits of throw.

The driving of both the needle bar and the means for imparting fore-and-aft motion to the looper from the same jack-shaft 38 by wheels fast thereon insures perfect harmony in the movement of the needle and looper in the direction of needle travel; elevation and depression of the looper by the eccentric pin 67 insures accurate positioning of the rigid butt of the looper point structure vertically with respect to the needle path at each end of its fore-and-aft travel; and the operation of the looper

on the main shaft permits,—by the variability of the shape of the cam slot to give any cam pitch desired,—that the velocity at which the looper point structure moves to engage and disengage the loops may be made whatever may be desired to insure most effective operation, and the extent of in-and-out throw being similarly defined as desired. In setting and timing these parts, wrist pin 67 is made to throw a little farther over center one way than the other, so that while the relatively rigid looper point is brought below the arc of needle passage at one end of its throw it stops above the needle line at the other end of its throw, and link 73 is arranged to pass dead-center while the looper is at the ends of its throw, so that the looper may dwell materially at the extremes of its fore-and-aft movement.

To cause the looper to spread the loop for reception of the needle I mount upon the post 16 a stationary cam 76 formed as an L-shaped arm having its upper cam surface 77 disposed in the path of travel of the finger 50 of the pivoted looper member 47, so that as the looper moves from right to left (Fig. 2) or "down" and "aft" toward the retracted position of the needle, the finger 50 striking on the upper edge of cam 76, tilts the looper member 47 on its pivot 46, raising the point 48 away from the toe 45 of the rigid looper foot. To accommodate the looper foot when it lies below the plane of passage of the needle in loop-presenting position, I form in the surface of the presser foot a recess 78 into which the looper foot may be depressed as shown in Fig. 4.

For a simple and effective take-up action to handle the needle thread in coöperation with the looper mechanism I arrange the take-up arm 80 at the front end of the machine, pivotally mounting said arm as at 81 on the end of a vertical link 82 which is pivoted to the frame post 16 as at 83 and in the take-up arm intermediate the pivotal point 81 and its acting end I form an aperture for engagement with a wrist pin 85 preferably integral with, but eccentric to the axis of, the main shaft 40. Appropriate tension devices and thread guides are provided on the machine, 86 representing a usual tension device from which the thread is run through an aperture on the active end of the take-up 115 80 and thence beneath a thread guide and brake spring 87, carried by the needle bar, 120 to the needle eye.

In the operation of the machine, as shown in Figs. 8 and 9, a node of goods is elevated through the presser foot opening 18 and the needle moving forward penetrates 125 into and emerges from the upper surface thereof, working wholly above the presser foot. As the needle advances, the oppositely oscillating rock shaft 68 carries the looper bar rapidly to its forward limit of 130

- throw; the needle retracts sufficiently to form a loop *l* in the needle thread, as shown in Fig. 8; the looper point structure 42 is moved rapidly inward or toward the operator by the operation of cam 65 imparted to lever 60, and in such movement takes the loop *l* on the looper point structure. In this position the finger 50 of the relatively movable looper point member 47 is 10 out of engagement with the cam 76 and consequently spring 50 maintains the looper point members closed, so that both the point 48 and the foot 45 pass above the needle and enter the loop. As the needle retracts, wrist pin 67 oscillates toward the position shown in Fig. 2, passing over vertical center and so causing the looper point structure as a whole to rise above the work and pass a'ft across the opening in the presser foot; the 15 throw of the eccentric pin 67 being sufficient to depress the foot 44 so that its toe 45 lies below the line of passage of the needle in the recess 78 of the presser foot as shown in Figs. 2 and 7. During this operation the 20 finger 50 of looper member 47 engages the cam face 77 of arm 76 which restrains it against descent and forces the spreader point 48 to raised position inward from the path of needle travel and above the path of 25 the same. During the last part of this cycle of movement of the looper the feed works to carry the goods toward the rear of the machine so that when the needle starts on its next penetrating stroke the loop *l* is expanded as indicated in Fig. 9; assuming a 30 triangular form with one limb leading from the point of emergence of the loop from the work up to the shoulder 49 which is above and inward from the needle path and the other limb of the loop leading below the 35 elongated foot 44, and thence with an upward trend passing below the needle path to the shoulder 49. I find that by such a looper construction I can insure positive 40 presentation of the loop in such spread condition that the needle must pass therethrough on a penetrating stroke and this regardless of any length of stitch for which the machine may be adjusted. The elongated foot 44 holds down the lower run of the thread loop in such position that the needle thread may pass thereover regardless of the length of feed between stitches, even though the feed length be sufficient to carry 45 the point of emergence of the loop being manipulated beyond the end of the presser foot opening 18. When the needle starts on its next penetrating stroke, the looper point dwells practically stationary until 50 the needle has passed through the thread loop, and then the action of the cam 65 carries the looper point structure as a whole rapidly out of the loop toward the rear of the machine, so that the take-up 55, performing its active operation at approxi-
- mately this time, in conjunction with the now-forwardly-moving needle, sets the previously laid loop.
- While I have herein described in some detail a particular embodiment of my invention which I have found to be practically efficient, it will be apparent to those skilled in the art that changes in detail of construction might be made without departure from the spirit of my invention and within the scope of the appended claims.
- What I claim is:
1. In a sewing machine stitch forming mechanism, the combination with a needle, of looper mechanism, comprising a looper bar structure, a middle fulcrum therefor constituting of said bar a lever of the first order, means having flexible connection with said bar for imparting motion to the power-receiving end thereof in a plane to give its point-end an in-and-out movement across the needle path, and means for shifting the middle fulcrum of said lever fore-and-aft, thereby to actuate said bar as a lever of the third order, to move the looper point fore-and-aft with said flexible connection as a fulcrum.
  2. In a sewing machine stitch forming mechanism, the combination with a needle, of looper mechanism, comprising a looper bar structure, a middle fulcrum therefor constituting of said bar a lever of the first order, said fulcrum comprising an eccentric oscillating member, means to vibrate the end of said looper bar on said fulcrum, said means providing a sliding flexible connection with the looper bar on which said bar fulcrums transversely to the middle fulcrum as a lever of the third order.
  3. A sewing machine stitch forming mechanism comprising in combination a reciprocating needle, a looper-bar structure comprising a lever of the first order, having a point structure at one end, a movable middle fulcrum for said bar, means for moving said fulcrum up and down and fore-and-aft with respect to the line of needle passage and means for moving the power receiving end of said bar in and out with respect to said line of needle passage, transversely to the plane of the first said movement, to vibrate said bar on its middle fulcrum.
  4. In a sewing machine stitch forming mechanism, the combination with a pivoted needle bar, a curved needle, and means for operating the needle bar, of a shaft parallel with the needle bar axis, means to rock said shaft, a fulcrum member eccentrically carried by said shaft, a looper bar structure pivoted on and carried by said fulcrum member for vibration in a plane parallel with the shaft axis and for bodily movement fore-and-aft and up-and-down with said fulcrum member, and means for

imparting the stated vibration to said looper bar structure.

5. In a sewing machine stitch forming mechanism, the combination with a pivoted 5 needle bar, a curved needle therein, and means for vibrating said needle bar, of a shaft concentric with the needle bar axis, a fulcrum member eccentrically carried by the said shaft, means to rock said shaft, a 10 looper bar lever of the first order pivotally carried by said fulcrum member, said lever vibratable upon its pivotal axis in a plane parallel with the axis of the shaft and bodily movable fore-and-aft with respect to the line of passage of the needle 15 with said fulcrum member, means for imparting to said looper bar lever the stated vibration working in a plane parallel with the axis of said shaft, and a universal sliding joint between the power-receiving end 20 of said looper lever and said moving means.

6. In a sewing machine, stitch forming mechanism comprising in combination a pivoted needle bar, a shaft parallel with 25 the needle bar axis, a looper bar connected for movement with said shaft, a power shaft, a jack-shaft, gearing connections between said power and jack-shafts, operating connections from one end of said jack- 30 shaft to the needle bar and operating connections from the other end of said jack-shaft to the shaft for the looper bar.

7. In a sewing machine, stitch forming mechanism comprising in combination a pivoted needle bar, a looper-operating shaft, a looper lever eccentrically connected with said shaft and bodily movable 35 thereby in a plane parallel with the plane of needle bar oscillation, a power shaft and operating connections between said power 40 shaft and the needle bar and looper-operating shaft for simultaneously oscillating said needle bar and said looper-operating shaft in opposite directions through a portion of their throws.

8. A sewing machine stitch forming mechanism comprising in combination a pivoted needle bar, a bodily movable looper, a shaft carrying said looper in eccentric 50 connection therewith for bodily movement, a power shaft, a jack-shaft driven thereby, operating connection between said jack-shaft and the pivoted needle bar, and operating connections between said jack-shaft 55 and the oscillating looper carrying shaft, comprising direction reversing gearing and a link connection with the rotating jack-shaft.

9. Sewing machine stitch forming mechanism, comprising a needle, means to reciprocate it, a looper structure, means to vibrate said looper structure in and out across the path of needle reciprocation at the ends of its fore-and-aft throw, an oscillating shaft for removing said looper

bodily fore-and-aft, and means for oscillating said shaft comprising a constantly rotating part and connections between said constantly rotating part and the oscillating shaft including a link crank-connected 70 to the constantly rotating part and arranged to pass dead-center when the oscillating part is at its extreme of oscillation, whereby the looper may substantially dwell in its bodily fore-and-aft movement 75 during its in and out vibration.

10. In a sewing machine, stitch forming mechanism comprising in combination a reciprocating needle, an oscillating needle bar, a shaft parallel with the axis of oscillation of said needle bar, a fulcrum block eccentrically mounted on said shaft, a looper lever pivoted on said fulcrum block for vibration transversely to the plane of operation of the needle bar and movable 80 bodily by oscillation of said shaft, in fore-and-aft direction and up and down, means for oscillating said shaft to cause said shaft to dwell at its extreme of oscillation, and means to vibrate said looper in and out 85 during the respective dwells in its fore-and-aft movement.

11. In a sewing machine stitch forming mechanism, a looper for 6-way movement pivoted between its ends, for vibration in 95 one plane, means to vibrate said lever movable only in said plane, a flexible-slide-joint connection between said moving means and said lever whereon said lever may fulcrum for movement in a plane transverse to its 100 plane of vibration, and means for moving the pivotal axis of said lever bodily to cause movement of said looper, fore-and-aft and up-and-down in a plane transverse to said plane of vibration with the joint connection 105 as a fulcrum.

12. Sewing machine stitch forming mechanism, comprising, in combination, a frame, a needle bar pivoted in said frame, a looper carrying shaft parallel with the pivotal axis 110 of the needle bar, a fulcrum block eccentrically mounted on said shaft for bodily movement therewith in a plane parallel with the plane of oscillation of the needle bar, a looper pivoted to said block for vibration 115 in a plane transverse to the first said plane, a power shaft, a cam on said power shaft, a lever actuated by said cam, a sliding universal connection between the power applying end of said lever and said looper, a 120 transverse shaft extending through said frame, gearing connections between said power shaft and transverse shaft, a crank and link connection between said transverse shaft and the needle bar, and connections between said transverse shaft and the fulcrum-block-carrying shaft for oscillating the last 125 said shaft, comprising motion reversing means and a link having crank connections with the transverse shaft arranged to pass 130

dead-center when the fulcrum-carrying shaft is at its limits of oscillating movement.

13. Sewing machine stitch forming mechanism, comprising in combination with a presser foot a reciprocating needle working across one side of the presser-foot, a looper member working on the same side of the presser foot, means for imparting six-way cyclic motion to said looper member, a second looper member carried by the first, and stationary means, acted on by the second said looper member, during its movement with the first said member, for causing opening and closing relative movement of said members, respectively to spread and to take the loop.

14. Sewing machine stitch forming mechanism, comprising in combination a reciprocating needle, and a coöperating looper comprising a relatively rigid member, means for imparting six-way cyclic motion thereto including movement fore and aft of the plane of needle passage, a relatively yielding member carried by said relatively rigid member, and movable with respect to said fixed member to close or open position, and fixed cam means coacting with said relatively yielding member during its bodily, fore and aft movement with the relatively rigid member, arranged to cause relative movement between said two members.

15. Sewing machine stitch forming mechanism, comprising in combination a looper member, providing an elongated foot and toe, an auxiliary looper member, carried by the first, providing a looper point, means normally to hold said point and toe in co-operating closed position jointly to enter a loop, means for moving the first said member in a cyclic course including movement fore and aft with respect to the needle-travel, and a stationary cam coacting with the second said member at one end only of its fore and aft throw to cause its points to separate from the toe to spread the loop.

16. In a sewing machine stitch forming

mechanism, the combination of a looper member having a foot, a coacting pointed looper member bodily movable therewith and movable relative thereto, means to move 50 said members bodily together in a 6-way movement and relative to each other to present the foot and point jointly above the needle path at one extreme of the 6-way movement and to present the foot and point 55 respectively on opposite sides of the needle path at the other extreme of the 6-way movement, thereby to insure spreading of the loop.

17. Sewing machine stitch forming mechanism, comprising in combination a reciprocating needle, a looper member having an elongated foot 44, a coacting looper member having a point 48, a pivotal connection between said members, whereby they move 65 jointly in bodily movement and relative to each other on the pivot, means for moving one of said members in a six-way cyclic path and fixed cam means coöperating with the other member to cause relative movement 70 between said members in the course of their bodily displacement, whereby the point and foot of said members are separated at one end of their throw and are brought together at the other end of their throw. 75

18. Sewing machine stitch forming mechanism comprising in combination a needle, looper mechanism provided with an elongated foot and a coöperating point relatively movable to open or closed position, means to 80 operate said looper member to cause said foot and point while closed to enter a loop above the needle at one end of their throw and to cause the foot to descend below and the point to stand above the path of needle 85 operation at the other end of their throw.

In testimony whereof I hereunto set my hand in the presence of two witnesses.

JAMES WHITELAW.

In the presence of—

J. D. RIPPEY,

L. C. KINGSLAND.
